(57) CLAIM

The ornamental design for a folding mobile phone as shown and described.

DESCRIPTION

1. Folding mobile phone

2. Folding mobile phone

1.1 : Front

1.2 : Back

1.3 : Left

1.4 : Right

1.5 : Top

1.6 : Bottom

1.7 : Front, left, bottom side perspective view

1.8 : Back, right, bottom side perspective view

1.9 : Front view of folded state

1.10 : Back view of folded state

1.11 : Left view of folded state

1.12 : Right view of folded state

1.13 : Top view of folded state

1.14 : Bottom view of folded state

1.15 : Front, left, bottom side perspective view of folded state

1.16 : Back, right, bottom side perspective view of folded state

2.1 : Front

2.2 : Back

2.4 : Right

2.5 : Top

2.6 : Bottom

2.8 : Back, right, bottom side perspective view

2.9 : Front view of folded state
2.10 : Back view of folded state
2.11 : Left view of folded state
2.12 : Right view of folded state
2.13 : Top view of folded state
2.14 : Bottom view of folded state
2.15 : Front, left, bottom side perspective view of folded state
2.16 : Back, right, bottom side perspective view of folded state
 The broken lines shown in the drawings illustrate portions of the folding mobile phone and form no part of the claimed design.

1 Claim, 32 Drawing Sheets
